(57) **CLAIM**

I claim the ornamental design for a card holder, as shown and described.

DESCRIPTION

FIG. 1 is a right, front perspective view of a card holder according to an embodiment of the invention, where a left, front perspective view of the card holder shown in FIG. 1 is a mirror image of FIG. 1.

FIG. 2 is a left, rear perspective view of the card holder of FIG. 1, where a right, rear perspective view of the card holder shown in FIG. 1 is a mirror image of FIG. 2.

FIG. 3 is a top plan view of the card holder of FIG. 1, where a bottom plan view of the card holder shown in FIG. 1 is the same as FIG. 3.

FIG. 4 is a right elevation view of the card holder of FIG. 1, where a left elevation view of the card holder of FIG. 1 is a mirror image of FIG. 4.

FIG. 5 is a front elevation view of the card holder of FIG. 1; and,

FIG. 6 is a rear elevation view of the card holder of FIG. 1.
